DESIGN FOR A SCREW PLUG

William J. Janning, Dayton, Ohio, and Frank F. Joyner, Burbank, Calif.

Application September 11, 1943, Serial No. 111,104

Term of patent 7 years

To all whom it may concern:

Be it known that we, William J. Janning and Frank F. Joyner, both citizens of the United States and residents, respectively, of Dayton, county of Montgomery and State of Ohio, and Burbank, county of Los Angeles and State of California, have jointly invented a new, original, and ornamental Design for Screw Plugs, of which the following is a specification, reference being had to the accompanying drawing, forming a part thereof.

Fig. 1 is a top plan view of a screw plug showing our new design.

Fig. 2 is a side elevational view thereof.

Fig. 3 is a bottom plan view thereof.

We claim:

The ornamental design for a screw plug, as shown.

WILLIAM J. JANNING.
FRANK F. JOYNER.
